UNITED STATES PATENT OFFICE.

RICHARD SAVAGE, OF SAN FRANCISCO, CALIFORNIA.

HEATING AND COOKING RANGE.

SPECIFICATION forming part of Letters Patent No. 392,462, dated November 6, 1888.

Application filed February 23, 1887. Serial No. 228,581. (No model.)

To all whom it may concern:

Be it known that I, RICHARD SAVAGE, of the city and county of San Francisco, State of California, have invented an Improvement in 5 Heating and Cooking Ranges; and I hereby declare the following to be a full, clear, and exact description of the same.

My invention relates to a stove or range so constructed as to be employed for the ordinary purposes of cooking, and also to supply heated air, which may be conveyed to any desired point from the range.

It consists of a base or cold-air chamber under the stove or range, into which pure air is received from beneath or outside the house, a fire-box, grate, and ash-pan of the usual or any suitable construction, a top arranged in the usual manner for cooking, and an oven, and in combination with these of a series of flues 20 and passages through which air is admitted and conducted around the heating flues or spaces to a suitable discharge, from which it is conveyed away.

It also consists in a means for lining or protecting the exterior plates, so as to reduce the radiation of heat therefrom.

Referring to the accompanying drawings for a more complete explanation of my invention, Figure 1 is a section taken through the lines 30 *a b* of Fig. 2. Fig. 2 is a section taken through *g h* of Fig. 1. Fig. 3 is a section taken through *e f* of Fig. 2. Fig. 4 is a section taken through *c d* of Fig. 2. Fig. 5 is a detail of the joints.

In the ordinary construction of what are 35 known as French ranges, walls of brick surround the fire-place and oven, and the metal top is supported by these walls, cooking being carried on within the oven and upon the top of the range. In the ordinary cooking- 40 stove a similar fire-place, oven, and heat flues or passages are constructed, and there is a single outer wall of iron, through which a large portion of the heat of the stove is radiated into the room. My invention is designed to utilize 45 this heat and economize it for the purpose of warming distant or adjacent rooms or halls. For this purpose I provide the stove or range with double walls and a series of heat-saving 50 passages, together with inlet and outlet passages for the air.

A is the base-plate or bottom of the range

or stove, and *B* *B* are side walls forming the exterior. *C* is the top. *D* is the fire-place having the usual lining of iron or fire-brick, *E*, and the grate *F* at the bottom; and *G* is the 55 ash-pit. *H* is the oven. These parts are similar in construction to those now in use.

In the construction of the different parts of my stove or range I form channels, as shown plainly at *a'*, Fig. 1, by raised flanges cast with 60 the plates, and between which is a space of sufficient width to receive the edges of the side plates or the plates forming the oven or other part of the stove or range where it is desired to make a perfectly air-tight joint, and this is 65 more necessary in this case, as the smoke and products of combustion must be kept entirely out of the air-spaces. The edges of the various plates when they are put together enter the grooves or channels *a'*, and are set in any 70 suitable cement which will make a perfect joint.

In the construction of my stove or range the exterior walls, *B*, and top and bottom plate are enough larger than the portion needed for 75 containing the fire-place, oven, and ordinary heat-passages to permit the surrounding passages or heat-saving spaces *I*, which are formed around the fire-place *F* and around the oven *H*, as shown. Beneath the bottom plate, *A*, 80 of the range is a base, *J*, which is preferably made hollow, and has an air-inlet, *K*, opening into it at any suitable point. *L* are openings from this hollow base into the passages or chambers *I*, before described. These openings 85 allow the air to pass upward from the base into the heating-spaces *I*, surrounding the ash-pit and fire-place, and also surrounding the oven and the fire-flues *M*, which pass around the oven. These flues *M* are arranged in the 90 usual manner, as plainly shown in Figs. 1 and 2, so that the heat and products of combustion from the fire-place *D* pass above the oven, thence down behind it, thence beneath the bottom, diagonally toward the left lower corner, as shown in Fig. 1, being directed to this point by a diaphragm or partition, which is shown in the dotted lines at *N*, and from this point the flame passes backward into the vertical passage *M* at the rear of the oven, rising 95 and passing out at the pipe or chimney *O*. The heat-producing air-passages *I* extend 100

around the sides of the oven and exterior to the heat-producing spaces M, so that while the heat acts upon the oven in the usual manner it also acts through the outer walls to heat the air in the spaces I which surround the oven. In order to still further increase this heating capacity the plate P, which extends upward between the heat-passage M and the air-passage I, as shown in Figs. 1 and 3, 10 is provided with a series of pins or equivalent projections, Q, which are cast in the plate, so that one end of the pins extends into the heat and flame passage M, while the other end extends into the air-passage I on the outer side. These pins or projections, becoming heated, will assist to heat the air which rises from the openings L in the base-plate and passes over the pins as it rises.

20 R R are vertical pipes standing within each space M at the rear end of the oven, and the lower ends of these pipes connect with the cold-air chamber J, beneath the base-plate of the stove, and the air which passes up through these pipes is delivered through the elbow at 25 the upper end into the air-passage I at that end of the stove or range, and is mixed with the air which has already entered through the openings L in the base-plate.

In order to prevent radiation from the exterior plates of the range a non-conducting lining, t, is fixed to them, as follows: These plates are cast with small wrought-iron pins projecting inwardly from them. I have found a very convenient way to place the ordinary 30 French wire-nails in the mold, and when the iron is poured in to form the plates it surrounds these pins and holds them firmly, the points projecting inwardly. I then take sheets of asbestos or other suitable non-conducting 35 material and fit it upon these plates, the ends of the nails passing through the sheets, so that the points may be bent down upon the inside afterward and thus hold them firmly in place. This prevents almost entirely the radiation and escape of heat from the sides of the 40 stove or range. The top over the fire and oven is left exposed to the full force of the heat and flame from the fire-place and the flues or passages which extend beneath it, so that culinary 45 vessels may be employed upon the top of 50

the range or stove in the usual manner for cooking. That portion of the box over the heat-saving flues or spaces is lined in the same manner as the ends and back to prevent loss of heat.

55 The hot-air outlet is shown in the present case at S, Fig. 2, at the front of the stove or range; but it will be manifest that it may be taken out at any convenient point of the range to suit its position and the direction in which it is desired to carry the heated air. A pipe may be connected with this outlet and may be carried horizontally to a dining or other room or rooms upon the same floor with the range and to a considerable distance by making a 60 slight rising inclination of the pipe as it passes away from the range, and branch pipes may be carried up through the walls to the upper rooms, which are conveniently located with reference to the kitchen, so that several rooms 65 may be heated by the surplus heat taken from the kitchen stove or range, and the atmosphere of the kitchen will at the same time be much reduced and made more comfortable to the occupants.

70 Having thus described my invention, what I claim as new, and desire to secure by Letters Patent, is—

A stove or range having a flat top for the reception of cooking-vessels, and a fire place or oven in the body of the range and below this top with the usual surrounding heating flues and passages, in combination with an exterior wall forming an air-inlet chamber beneath, and secondary passages I outside of the interior 80 heat-passages, with pins Q, projecting through the intermediate walls, P, from the heat-passages into the exterior ones, and a series of vertical pipes or flues, R R, passing through the rear heat-passages, M, and having their upper ends curved or bent, so as to discharge 85 into the exterior surrounding passages, I, substantially as herein described.

90 In witness whereof I have hereunto set my hand.

RICHARD SAVAGE.
